UNITED STATES PATENT OFFICE.

JOHN WEBSTER TRAUGER, OF BINGHAMTON, AND CLARENCE JOHN SMETHERS, OF JOHNSON CITY, NEW YORK, ASSIGNEES TO FAIR PLAY CARAMELS, INC., A CORPORATION OF NEW YORK.

METHOD OF PACKING CARAMELS OR CONFECTIONERY.

Application filed May 1, 1926. Serial No. 105,949.

This invention relates to a package and a method of packing confectionery therein of the type usually known as suckers which are impaled upon a stick which serves as a handle for holding the same while it is being consumed.

It is an object of this invention to provide a method of packing such confectionery whereby the impaling sticks are arranged in upright positions so that single pieces can be readily removed from the container, and which presents an orderly array likely to promote sales.

The invention comprises the novel method hereinafter described and more particularly pointed out and defined in the appended claims.

In the accompanying drawings which illustrate the preferred method of carrying out this invention, and in which similar reference numerals refer to similar features in the different views—

On the drawings:

Figure 1 is a top plan view of a container 25 with the cover removed illustrating the method of packing the confectionery.

Figure 2 is a vertical sectional view of the container.

As shown on the drawings:

In carrying out this invention, the operator takes a suitable container 1 which is shown as in the form of a box, and places the wrapped and impaled pieces 2 of confectionery therein in adjacent series 3 with the 35 impaling sticks 4 in upright position, the pieces in each series are packed closely together and one series is packed closely against its adjacent series, consequently the impaling sticks 4 are maintained in sub-

stantial parallel upright relation. A cover 5 having deep lateral sides 6 is then applied to the container, and rests upon the impaling sticks which project above the top of the container 1.

This method also produces a novel package 45 in that the impaling sticks project above the container and support the cover which encloses the impaling means. When the cover is removed the sticks will be brought into full view, and a piece of confectionery may 50 readily be removed by grasping its impaling stick.

We are aware that many changes may be made, and numerous details of construction may be varied through a wide range without departing from the principles of this invention, and we therefore do not purpose limiting the patent granted hereon, otherwise than necessitated by the prior art.

We claim as our invention:

1. The method of packing impaled pieces of confectionery which consists in packing said pieces in upright position in a container with the impaling sticks projecting above such container and slipping a free cover over 65 the container so that the cover is supported on the tops of said impaling sticks.

2. An article of manufacture comprising a container consisting of a body portion, impaled pieces of confection packed side by 70 side in said portion with the impaling means extending above the body portion, and a free cover telescoped over the body and supported upon said impaling means.

In testimony whereof, we have hereunto 75 subscribed our names.

JOHN WEBSTER TRAUGER.
CLARENCE JOHN SMETHERS.
